UNITED STATES PATENT OFFICE.

WILLIAM G. WEHR, OF EAST CLEVELAND, OHIO, ASSIGNOR TO THE CLEVELAND CRANE & ENGINEERING COMPANY, OF WICKLIFFE, OHIO, A CORPORATION OF OHIO.

GRAB.

Application filed August 25, 1925. Serial No. 52,304.

The present invention relates to improvements in grabs, and more particularly to grabs of the type in which load engaging hooks or clamping jaws are so mounted that they are urged by gravity toward load engaging position and are maintained in engagement with a load by the weight thereof.

It is an object of the present invention to provide a magnetically actuated grab in which the interruption of electric current to the electro-magnetic actuator will not cause the release of the load.

The further object is to provide a grab in which the hooks or jaws are so connected to the suspension member or headblock and the movable part of the solenoid carried by the suspension member that the actuation of the solenoid will cause the hooks or jaws to be moved to open or load releasing position and to be held in such a position until the current through this solenoid is interrupted.

With the above and other objects in view, the invention may be said to comprise the device as illustrated in the several modifications shown in the accompanying drawings hereinafter described and particularly set forth in the appended claims together with such variations and modifications thereof as will be apparent to one skilled in the art to which the invention appertains.

Reference should be had to the accompanying drawings, forming a part of this specification, in which Fig. 1 is a side elevation of a two jaw grab embodying the invention; Fig. 2 is a top plan view of the grab shown in Fig. 1; Fig. 3 is the side elevation showing invention applied to a modified form of grab; Fig. 4 is an end elevation of the grab shown in Fig. 3; Figs. 5 and 6 show side elevations and a top plan view, respectively, of a grab provided with a series of radially movable jaws and showing the present invention applied thereto; Figs. 7, 8 and 9 show a side elevation, an end elevation and a top plan view, respectively, of the grab embodying the invention and having two jaws provided with laterally spaced load engaging arms; Figs. 10 and 11 show side elevations and a top plan view showing the invention applied to a grab of the internally engaging or expander type; and Figs. 12 and 13 are side and end elevations showing the

invention applied to a grab designed for handling loose material such as waste paper.

Referring first to Figs. 1 and 2, the grab is provided with a suspension member or head block 1 upon which is mounted a sheave 2 which receives the loop of a hoist cable 3 by means of which the grab and the load carried thereby may be raised or lowered. The head block 1 has a lower portion 4 which is hollow and cylindrical forming a casing for the coil 5 of a solenoid which is connected by a suitable flexible conductor 6 with a suitable source of current.

The coil 5 is wound upon a cylindrical tube 7 at the center of the casing 4 and the core 8 of the solenoid is slidably mounted within the tube 7.

The lower end of the casing 4 is provided with an opening 9 through which the lower end portion of the core 8 extends, the core 8 having a sliding fit in the opening 9 and being provided with an enlarged upper portion 10 which has a sliding fit in the tube 7 and which provides a shoulder engageable with the bottom of the casing 4 to limit the downward movement of the core.

At its lower end the core 8 is connected to the center of a horizontal disposed spacer bar 11 to the opposite ends of which are pivoted the jaws 12 which have suitable engaging prongs 13 at their lower ends and inwardly curved upper end portions 14 above their pivotal connections to the spacer bar 11. The bar 11 may be provided with a plurality of holes 11^x at the ends thereof to receive the pins connecting the jaws 12 thereto to adjust the grab for different sized loads.

The upper inwardly projecting ends of the jaws 12 are connected to the head block 1 by means of links 15 which are pivoted at their outer ends to the upper end portions 14 of jaws, and at their inner ends to ears 16 formed integrally with the casing 4 on opposite sides thereof. The normal position which the jaws 12 will assume when the solenoid coil 5 is deenergized is substantially shown in full lines in Fig. 1.

Since the core 8, the spacer bar 11, and the jaws 12 supported on the bar 11, will move downwardly by gravity until the enlarged portion 10 of the core 8 rests upon

the bottom of the casing 4, the links 15 during the downward movement of the core and jaws, move toward horizontal position causing the upper ends of the jaws 12 to move outwardly and the lower ends thereof to move inwardly. When current is passed through the solenoid coil 5 the core 8 is moved upwardly within the coil 5 lifting the spacer bar 11 and causing the links 15 to swing upwardly towards vertical position, drawing the upper ends of the jaws 12 inwardly and spreading the lower ends thereof apart, this position of the grab being shown in dotted lines in Fig. 1.

15. In the operation of the grab the overhead support from which the grab is suspended will be shifted to a point directly above the load to be lifted and the solenoid will be energized to move the jaws to open position. 20. The open grab will then be lowered until the jaws thereof are upon the opposite sides of the article to be lifted and the current through the solenoid will be interrupted to permit the jaws to fall by gravity into gripping 25. engagement with the article. When the article so engaged is lifted the weight thereof is added to the clamping jaws tending to cause the jaws to move toward their lowest position with respect to the head block 1 and into tighter gripping engagement with the load. Ordinarily the solenoid coil 5 will be provided with sufficient turns to lift the jaws and move them to releasing position only when they are not 30. carrying a load. In such case it will be necessary to deposit the load upon the ground or upon the pile to take the weight thereof from the grab before the grab is released. It is obvious, however, that if it 35. is desirable a solenoid may be provided which has sufficient power to release the grab while carrying a load and allow the load to drop from the grab.

40. In Figs. 3 and 4 there is shown a grab differing somewhat in construction from that shown in Figs. 1 and 2, and in these views the parts corresponding to parts shown in Figs. 1 and 2, and above described, are designated by the same reference numerals with the added exponent "a".

45. The head block 1^a is substantially the same as head block shown in Fig. 1 except that it has at its upper end an eye 17 to which a hoisting cable may be attached. 50. The solenoid core 8^a, spacer bar 11^a, and actuating links 15^a, are exactly the same as in the modification above described. The clamping jaws 12^a, however, are provided with laterally bent lower portions forming 55. spaced arms 18 connected by a brace 19 and having load engaging plates 20 secured to the inner sides thereof. The grab shown in Figs. 3 and 4 is suitable for handling pipes, barrels, paper or other similar cylindrical articles, the operation of this grab be-

ing exactly the same as described above in connection with Figs. 1 and 2.

60. Figs. 5 and 6 illustrate the application of the invention to a grab which is provided with a series of angularly disposed radially movable jaws. Any number of radially disposed jaws may be employed, the three jaw grab shown in Figs. 5 and 6 being illustrative of the radially movable jaw type of grab. The parts in these views corresponding to the parts shown and described in connection with Figs. 1 and 2 are designated by the same reference numerals with the added exponent "b".

65. The head block 1^b is identical with the head block 1 in Figs. 1 and 2 except that there are three sets of ears 16^b spaced 120° apart at the lower end thereof. Three radially movable jaws 12^b are provided instead of the two oppositely disposed jaws shown in Fig. 1. The jaws 12^b are substantially identical with the jaws 12 and have their upper ends connected by actuating links 15^b to the ears 16^b. On the head block in this modification the spacer 11^b is in the 70. form of a spider with arms extending from the center thereof at 120° to each other, each arm being pivotally connected at its outer end to one of the jaws 12^b and the central portion of the spider being connected to the core of the solenoid. It will be obvious that the lower ends of the jaws 12^b tend to move by gravity toward the vertical axis of the grab and that upon actuation of the solenoid the lower engaging ends of the jaws will be moved outwardly.

75. In Figs. 7, 8 and 9 of the drawing, the invention is shown applied to a grab of the type having oppositely disposed jaws with parallel spaced load engaging portions. 80. The parts in these views corresponding to parts shown in Fig. 1 are designated by the same reference numerals with the addition of the exponent "c".

85. The head block 1^c, in this case, is identical with the head block shown in Fig. 1 except that the ears 16^c upon opposite sides of the casing 4^c are spaced farther apart. The core 8^c of the solenoid extends through 90. and is rigidly secured to a rigid cross bar 21 by means of a nut 22 upon the lower end of the core. The spacer bars 11^c are secured centrally thereof to opposite ends of the cross bar 21 by bolts 23, and to the opposite ends of the spacer bars 11^c are pivoted the load engaging jaws 12^c which are substantially identical in construction with the jaws 12^b in Fig. 1. Means is provided for moving the pairs of jaws on opposite sides of the head block 1^c simultaneously, 95. and to this end each jaw 12^c is connected at its upper end by a link 15^c with a cross rod 24 extending through the ears 16^c on opposite sides of the head block, and through the inner ends of the links 15^c. 100.

Spacer sleeves 25 are provided between the ears 16^c and the links 15, and the links 15 are clamped against the outer ends of the sleeves 25 by nuts 26 upon opposite ends of the rod 24.

It will be obvious upon comparison of Figs. 1 and 7 that the lifting of the solenoid core 8^c will cause the pairs of jaws on opposite sides of the head block to move simultaneously toward and away from each other to load releasing position, and that when the core 8^c is released the jaws will move by gravity into load gripping position.

In Figs. 10 and 11 the invention is shown applied to a grab of the type in which the jaws move outwardly instead of inwardly to grip the load. Parts of these modifications corresponding to parts shown in Figs. 1 and 2 are designated by the same reference numerals with the addition of the exponent "d".

The head block 1^d is substantially identical with the head block 1^b in Fig. 1, but the actuating rods 15^d are inclined downwardly from their points of attachment to the head block instead of upwardly as shown in Fig. 1, and the jaws 12^d are in the form of bell cranks which are pivoted at the angle between the arms thereof on a horizontal pin 27 passing through the lower end of the core 8^d and through the jaws 12^d. Each of the jaws 12^d has an arm extending outwardly from the pivot pin 27 and connected at its outer end to an actuating link 33 15^d, and an arm extending downwardly from the pivot pin 27 and provided on the outer side thereof with a series projection 28 for engaging the interior of a hollow article to be lifted by the grab. When solenoid is energized the jaws 12^d will be held in the position shown in full lines in Fig. 10 with the engaging arms thereof substantially at the plane of the core 8^d. When the core 8^d is released by interrupting the current through the solenoid coil the core 8^d and the jaws 12^d will drop downwardly causing the links 15^d and the outwardly extending arms of the jaws 12^d connected thereto to move inwardly and at the same time causing the engaging portion 28 to move outwardly into engaging position. The weight of the load supported by the jaws 12^d creates an added downward force on the pivot 27 tending to move the same downwardly and to press engaging portion 28 of the jaws into tighter engagement.

In Figs. 12 and 13 a further modification of the invention is shown. The parts corresponding to parts shown in Figs. 1 and 2 are designated by the same reference numerals with the addition of the exponent "e".

The head block 1^e is similar to the head block 1^a shown in Figs. 3 and 4 except that the attaching ears 16^e are adjacent the up-

per ends of the casing 4^e in place of adjacent the lower end. The core 8^e passes through and is secured to a rigid cross bar 29 by means of the nut 30, and to the opposite ends of the bar 29 the spacer bars 11^e are rigidly secured. The opposite ends of the parallel spacer bars 11^e are connected by parallel tie rods 31 which are threaded in their opposite ends and have nuts 32 which clamp the outer ends of the bars 11^e against the ends of spacer sleeves 33 which fit upon the rod 31 between the spacer bars. The jaws 12^e are rigidly secured to the spacer sleeves 33 adjacent the ends thereof and at the center of each sleeve 33 there is an inwardly extending arm 34 rigidly secured to the sleeve. Actuating links 15^e are pivotally connected to the inner ends of the arms 34 and extend upwardly therefrom to the attaching ears 16^e on the head block to which they are pivotally connected. The position normally assumed by the grab is shown by full lines in Fig. 12 which shows the core 8^e and spacer bars 11^e in their lowermost position in which the jaws 12^e are held by the links 15^e in their innermost or load engaging positions. When the solenoid is energized the core 8^e together with the spacer bars and jaws mounted thereon are lifted to position shown in dotted lines in Fig. 12. The upward movement of the jaws causes the arms 34 which are held by the actuating links 15^e to be rocked downwardly and the jaws 12^e each are fixed to the same sleeves as arms 34 to be rocked outwardly to load releasing position. In the operation of the grab shown in Figs. 12 and 13 the grab will be positioned over the loose material to be lifted, the solenoid will be energized to move the grab to open position and the grab will then be dropped into the material. The jaws or prongs will enter the material to be lifted and, upon release of the solenoid, will tend to move to load gripping position. When the grab is lifted the weight of the material engaged by the jaws or prongs 12^e will increase the gripping action causing the material between the prongs to be tightly gripped between the prongs.

Having described my invention, what I claim is:

1. A grab comprising a suspension member, a solenoid carried by said member, and having a movable core, load engaging jaws supported by the core of the solenoid, and actuating means interposed between the suspension member and jaws to actuate the jaws when the same are moved by the solenoid.

2. A grab comprising a suspension member, a solenoid carried by said member, and having a movable core, load engaging jaws supported by the core of the solenoid, and actuating links connected to the jaws and to the suspension member.

3. A grab comprising a head block, a solenoid mounted in the block and having a vertically movable core, jaws supported by the core and pivoted to swing about horizontal axes, and actuating links pivoted to the head block and to the jaws at points spaced from the pivotal axes thereof.
4. A grab comprising a suspension member, jaws suspended therefrom for movement by gravity to load engaging positions, and a vertically disposed solenoid mounted on the suspension member centrally thereof and having a core connected to the jaws to move and hold the same to load releasing position when the solenoid is energized, the weight of the core when the solenoid is deenergized acting to shift the jaws toward load engaging position.
5. A grab comprising a suspension member, a vertically movable member carried by the suspension member and normally held by gravity in its lowermost position with respect thereto, jaws pivoted to said movable member, means connecting the jaws and suspension member for automatically moving the jaws to load engaging position during downward movement of said movable member, and to releasing position upon upward movement thereof, and a solenoid for lifting said movable member to shift the jaws to releasing position.
6. A grab comprising a head block, load engaging jaws connected to the head block and adapted to move by gravity to load engaging position, and a solenoid carried by the head block, said solenoid having a vertically movable core connected to the jaws and adapted, when the solenoid is energized, to move the jaws to releasing position, the weight of said core when the solenoid is deenergized acting upon said jaws to move them toward load engaging position.
7. A grab comprising a head block, load engaging jaws, links connecting the upper portions of the jaws to the head block, and a solenoid carried by the head block and having a core connected with the jaws intermediate the ends thereof.
8. A grab comprising a head block, load engaging jaws pivotally connected at their upper ends to the head block and adapted to move by gravity to load engaging position, a vertically disposed solenoid mounted in the head block centrally thereof, said solenoid having a core connected to the jaws intermediate the ends thereof and adapted, when the solenoid is energized, to move the jaws to open position, and means for limiting the downward movement of the core.
9. A grab comprising a head block, load engaging jaws, links connecting the upper portions of the jaws to the head block, a solenoid mounted in the head block centrally thereof and having a vertically disposed core, means connecting the lower end of said core to said jaws intermediate the ends thereof, and means for limiting the downward movement of the core.
10. A grab comprising a head block, links pivoted at their inner ends to the head block, jaws pivotally connected to the outer ends of the links, and adapted to move bodily with respect to the head block, means connecting said jaws and cooperating with said links to cause the jaws to be normally held by gravity in load engaging position, and a solenoid having a vertically movable core connected to said connecting means for shifting the same to move the jaws to load releasing position.
11. A grab comprising a head block, links pivoted at their inner ends to the head block, jaws pivoted to said links, means for supporting said jaws comprising a rigid spacer pivoted to the jaws below the pivotal connections between the jaws and links and a member carried by the head block which is connected to the spacer and has a limited vertical movement with respect to the head, and means on the head for shifting said member to actuate the jaws.
12. A grab comprising a head block, a solenoid mounted in the head block, and having a vertically disposed core adapted to be lifted when the solenoid is energized, means for limiting the downward movement of the core, a rigid spacer carried by the core, jaws pivoted on said spacer, and actuating links connecting said jaws to the head block to move the jaws to open position when the same are lifted by the solenoid.
13. A grab comprising a head block, a solenoid carried by the head block and having a vertically movable core adapted to be lifted when the solenoid is energized and to drop by gravity when the solenoid is deenergized, means for limiting the downward movement of the core, load engaging jaws supported by the core, and means interposed between the head block and jaws for opening the jaws when the same are lifted by the solenoid and for closing the jaws upon release of the solenoid.
14. A grab comprising a suspension member, jaws pivotally suspended from said member, a vertically disposed solenoid carried by said suspension member and a weight connected to said jaws to close the same, said weight forming the core of said solenoid and acting to open the jaws when the solenoid is energized.

In testimony whereof, I hereunto affix my signature.

WILLIAM G. WEHR.
